UNITED STATES PATENT OFFICE.

OTTO KURZ, OF STURGIS, MICHIGAN, ASSIGNOR TO FOYER MANUFACTURING COMPANY,
OF STURGIS, MICHIGAN.

COLLAPSIBLE CARRIAGE.

No. 866,145.

Specification of Letters Patent.

Patented Sept. 17, 1907.

Application filed December 20, 1906. Serial No. 348,828.

To all whom it may concern:

Be it known that I, OTTO KURZ, a subject of the Emperor of Germany, residing at Sturgis, county of St. Joseph, State of Michigan, have invented certain new and useful Improvements in Collapsible Carriages, of which the following is a specification.

This invention relates to improvements in baby-carriages.

It relates particularly to improvements in folding 10 baby-carriages quite generally designated as perambulators or go-carts.

The objects of this invention are,—First, to provide an improved folding baby-carriage which is adapted to fold very compactly, and is, when erected, very strong 15 and rigid. Second, to provide an improved folding baby-carriage which is very quickly and easily operated to collapse, or to open or erect the same. Third, to provide, in a folding baby-carriage, an improved means for positively folding or erecting by a simple lever-like movement. Fourth, to provide, in a folding baby-carriage, an improved arrangement of the parts whereby the parts are securely locked in their erected 20 position. Fifth, to provide, in a folding baby-carriage, an improved seat support. Sixth, to provide, in a folding baby-carriage, an improved collapsible foot-rest. Seventh, to provide, in a folding baby-carriage, a combination foot-rest and pocket.

Further objects, and objects relating to structural details, will definitely appear from the detailed description to follow.

I accomplish the objects of my invention by the devices and means described in the following specification.

The invention is clearly defined and pointed out in 35 the claims.

A structure embodying the features of my invention is clearly illustrated in the accompanying drawing, forming a part of this specification, in which,—

Figure 1 is a side elevation view of my improved folding baby-carriage, the rear position of the back for the seat being indicated by dotted lines; Fig. 2 is a plan thereof; Fig. 3 is a side elevation showing the structure partially collapsed; Fig. 4 is an inverted plan of the structure collapsed; Fig. 5 is an enlarged detail cross-section taken on the broken line 5—5 of Fig. 1, showing structural details; Fig. 6 is an enlarged detail section taken on a line corresponding to line 6—6 of Fig. 1, showing the spring support for the rear end of the seat; Fig. 7 is an enlarged detail section taken on a line corresponding to line 7—7 of Fig. 1, showing the supporting clips for the wheel-supports; Fig. 8 is an enlarged detail section taken on a line corresponding to line 8—8 of Fig. 2, showing the structural details of the foot-rest.

In the drawing, the sectional views are taken looking in the direction of the little arrows at the ends of the

section lines, and similar reference characters refer to similar parts throughout the several views.

Referring to the drawing, the running-gear frame 1 is preferably formed of tubing bent into a U-shape. At the rear end of this frame is pivoted the handle 2, which is also preferably formed of tubing bent into a U-shape. On each of the side bars of the running-gear is a pair of clip-like hangers 3 for the wheel-supports 5. These hangers are preferably held in proper spaced relation by the bars 4. A brace or cross-piece 38 is provided for the frame towards its rear end. The wheel-supports 5 are preferably formed of rods, having downwardly projecting ends 6, which are provided with suitable journals for the wheels 7. The wheel-supports 5 are pivoted in the hangers, so that they are free to swing there- 70 in to permit the wheels being folded upon each other upon the running-gear frame, as clearly appears in Fig. 4. The wheel-supports 5 are provided with offsets forming crank-like arms 8, the offsets being preferably inclined downwardly toward the rear. 75

Pivoted to the side bars of the frame 1 by the pivots 11 and arranged above the arms 8 of the wheel-supports, is a pair of levers 9, their lower ends projecting downwardly and preferably on the outside of the arms, as clearly appears from the drawing. On the lower 80 ends of the levers are loops 12 adapted to embrace the crank-like arms of the wheel-supports. When the levers 9 are actuated, these loops engage the crank-like arms, serving to positively swing the wheel-supports in and out. The levers are also preferably arranged to hold the wheel-supports in both positions. The lower 85 ends of the levers are preferably connected by the cross-pieces 10 and 37 rigidly connecting them so that they serve to rigidly hold the wheel-supports in their erected position. The cross-piece 37 is preferably arranged so that it is substantially opposite the arms on the wheel-supports when in the erected position; see Fig. 5. The levers 9 and the connecting cross-piece 10 are preferably formed in one piece, as there illustrated.

The levers 9 are preferably connected to the handle 95 by links 20, so that, when the handle is swung forwardly, the upper ends of the levers are also swung forwardly, thereby collapsing the wheels, and on the rearward or upward movement of the handle, the wheel-supports are opened or erected. The links 20 are preferably 100 adapted to and, in the structure illustrated, do serve as arms or side bars for the seat. The structure is preferably locked in its erected position by the bail-like locking-bar 13, which is pivoted to the side bars of the running-gear at 14 and connected to the levers 9 by the 105 links 15, the links being mounted on the cross-rod 37. When the locking-bar 13 is thrown down into its lower position, in front of the seat, it is not in the way of the occupant of the carriage.

The seat 16 is supported at its forward end by the 110

cross-piece 36 having downwardly depending arms at each end, which are pivoted to the levers 9 by means of the cross-rod 37. The rear end of the seat is preferably supported by a spring device consisting of tubular spring casings 22, which are secured by pivots 23 to the side bars of the running-gear frame. Within these casings are coiled springs 24, on which the cross-piece rod 25 rests. This cross-rod 25 is provided with downturned ends 26, which are arranged through the bottoms of the casings 22, as clearly appears in Fig. 6. The rod 25 is secured to the underside of the seat by clips 27. The casings 22 are slotted to receive the cross-rod, as clearly appears in the drawing. This provides a spring support for the seat, and allows the same to swing forwardly and downwardly in collapsing the structure.

The back 17 of the seat is secured on the upwardly projecting ears 28 by the cross-rod 29. The back preferably consists of a U-shaped frame to the upper end of which and to this cross-rod is secured a suitable canvas. The upper end of the back is preferably supported by a bail 19, pivoted upon the links 20, the back being provided with loops 18 through which the bail is adjustably supported so that it may be held in its upright position, as shown by dotted lines in Fig. 1. When the structure is collapsed, this back folds forwardly upon the seat.

The foot-rest preferably consists of a piece of canvas fabric 33 suspended at its forward end from the pivoted bail-like cross-piece 31 adapted to be swung forwardly to elevate the foot-rest to the position indicated by dotted lines in Fig. 8, or to drop the same into the pocket 32 when swung to its rear position. The rear end of the foot-rest is secured to the cross-rod 37 on the levers 9. The foot-rest is provided with a foot-board 34. Below the foot-rest is a pocket 32, the sides of the pocket forming the sides of the foot-rest. The forward end of the pocket is secured to the cross-piece 30 on the running-gear frame. The foot-rest and pocket are preferably formed of one piece of material, as clearly appears from Fig. 8. To elevate and hold the foot-rest and pocket in an elevated position, when the structure is collapsed, I connect the same by straps 35 to the cross-piece 10 of the lower ends of the levers 9. It is evident that, when the upper ends of the levers are swung forwardly, their rear ends swing rearwardly, thereby lifting the foot-rest and pocket.

By forming and arranging the parts as I have illustrated and described, I secure a folding baby-carriage which may be quickly folded or erected, the parts being positively actuated. To fold the structure, it is only necessary to release the locking-bar 13 by lifting upwardly thereon, and then swing the handle forwardly. This can best be accomplished by grasping the forward end of the running-gear frame and the top of the handle 55 and bringing them together, lifting the parts from the floor, during the collapsing operation. To erect the structure, it is only necessary to reverse this movement, swinging the locking-bar down into its locking position, and it is impossible to collapse the same without releasing the lock.

My improved folding baby-carriage is strong and rigid and very durable. I have illustrated and described the same in detail in the form preferred by me on account of the structural simplicity and economy. I am, however, aware that it is capable of considerable

variation in structural details without departing from my invention, and I desire to be understood as claiming the same specifically, as illustrated, as well as broadly.

Having thus described my invention, what I claim as new and desire to secure by Letters Patent is:

1. In a collapsible carriage, the combination with a running-gear frame, of a handle pivotally connected to said frame; wheels; wheel-supports having arms thereon, pivotally secured to said frame; levers pivoted on said frame, arranged to engage said arms on said wheel-supports; operating connections for said levers to said handle; a bail-like locking-bar pivoted to said frame; links connecting said bar to said levers; a seat; a supporting bar for the forward end of said seat, having downturned ends pivoted on said levers; a spring support for the rear end of said seat, comprising tubular casings pivoted to said frame, coiled springs arranged in said casings, and a cross-bar pivotally secured to said seat, arranged to rest on said springs, having downturned ends arranged through the bottoms of said casings, a back for said seat pivotally secured thereto and adapted to fold forwardly thereon; a bail-like support for the upper end of said back, pivoted to said connecting links for said levers to said handle; loops on said back through which said support is arranged; a foot-rest of flexible material having a foot-board therein; a pivoted bail-like support for the forward end of said foot-rest; a cross-rod on said levers to which the rear end of the foot-rest is secured; a pocket arranged below said foot-rest, having sides adapted to serve as sides for said foot-rest; and straps connected to said pocket and to the lower ends of said levers, whereby said pocket and foot-rest are lifted upwardly when said levers are actuated to collapse the structure, for the purpose specified.

2. In a collapsible carriage, the combination with a running-gear frame, of a handle pivotally connected to said frame; wheels; wheel-supports having arms thereon, pivotally secured to said frame; levers pivoted on said frame, arranged to engage said arms on said wheel-supports; operating connections for said levers to said handle; a bail-like locking-bar pivoted to said frame; links connecting said bar to said levers; a seat; a supporting bar for the forward end of said seat, having downturned ends pivoted on said levers; a spring support for the rear end of said seat, comprising tubular casings pivoted to said frame, coiled springs arranged in said casings, and a cross-bar pivotally secured to said seat, arranged to rest on said springs, having downturned ends arranged through the bottoms of said casings; a back for said seat pivotally secured thereto and adapted to fold forwardly thereon; a bail-like support for the upper end of said back, pivoted to said connecting links for said levers to said handle; loops on said back through which said support is arranged; a foot-rest of flexible material having a foot-board therein; a pivoted bail-like support for the forward end of said foot-rest; a pocket arranged below said foot-rest, having sides adapted to serve as sides for said foot-rest; and straps connected to said pocket and to the lower ends of said levers, whereby said pocket and foot-rest are lifted upwardly when said levers are actuated to collapse the structure, for the purpose specified.

3. In a collapsible carriage, the combination with a running-gear frame, of a handle pivotally connected to said frame; wheels; wheel-supports having arms thereon, pivotally secured to said frame; levers pivoted on said frame, arranged to engage said arms on said wheel-supports; operating connections for said levers to said handle; a bail-like locking-bar pivoted to said frame; links connecting said bar to said levers; a seat; a supporting bar for the forward end of said seat, having downturned ends pivoted on said levers; a spring support for the rear end of said seat, comprising tubular casings pivoted to said frame, coiled springs arranged in said casings, and a cross-bar pivotally secured to said seat, arranged to rest on said springs, having downturned ends arranged through the bottoms of said casings; a back for said seat pivotally secured thereto and adapted to fold forwardly thereon; a bail-like support for the upper end of said back, pivoted to said connecting links for said levers to said handle.

material having a foot-board thereon; an adjustable support for the forward end of said foot-rest, for the purpose specified.

14. In a carriage, the combination with a running-gear frame, of a handle pivotally connected to said frame; wheels; wheel-supports having depending ends with wheel-journals thereon and having rearwardly and downwardly inclined offsets therein forming crank-like arms, pivotally secured to said frame; levers pivoted on said frame, projecting below the same; loops on said levers arranged to engage said arms on said wheel-supports; links connecting the upper ends of said levers to said handle; a seat; a foot-rest of flexible material having a foot-board therein; and an adjustable support for the forward end of said 5 foot-rest, for the purpose specified. 90
15. In a carriage, the combination with a running-gear frame, of a handle pivotally connected to said frame; wheels; wheel-supports having depending ends with wheel-journals thereon and having rearwardly and downwardly inclined offsets therein forming crank-like arms, pivotally secured to said frame; levers pivoted on said frame, projecting below the same; loops on said levers arranged to engage said arms on said wheel-supports; links connecting the upper ends of said levers to said handle; a seat; a foot-rest; a pocket arranged below said foot-rest, having sides adapted to serve as sides for said foot-rest and straps connected to said pocket and to the lower ends of said levers, whereby said pocket and foot-rest are lifted when the structure is collapsed, for the purpose specified. 95
16. In a carriage, the combination with a running-gear frame, of a handle pivotally connected to said frame; wheels; wheel-supports having depending ends with wheel-journals thereon and having rearwardly and downwardly inclined offsets therein forming crank-like arms, pivotally secured to said frame; levers pivoted on said frame, projecting below the same; loops on said levers arranged to engage said arms on said wheel-supports; links connecting the upper ends of said levers to said handle; a bail-like locking-bar pivoted to said frame; links connecting said bar to said levers; a seat; and connections from said foot-rest to said levers whereby said foot-rest is lifted when the structure is collapsed, for the purpose specified. 100
17. In a carriage, the combination with a running-gear frame, of a handle pivotally connected to said frame; wheels; wheel-supports having depending ends with wheel-journals thereon and having rearwardly and downwardly inclined offsets therein forming crank-like arms, pivotally secured to said frame; levers pivoted on said frame, projecting below the same; loops on said levers arranged to engage said arms on said wheel-supports; links connecting the upper ends of said levers to said handle; and connections from said foot-rest to said levers whereby said foot-rest is lifted when the structure is collapsed, for the purpose specified. 105
18. In a collapsible carriage, the combination with a running-gear frame, of a handle pivotally connected to said frame; wheels; wheel-supports having arms thereon, pivotally secured to said frame; levers pivoted on said frame, arranged to engage said arms on said wheel-supports; links connecting the upper ends of said levers to said handle; a bail-like locking-bar pivoted to said frame; links connecting said bar to said levers; a seat; a foot-rest of flexible material; an adjustable support for said foot-rest; and connections from said foot-rest to said levers whereby said foot-rest is lifted when the structure is collapsed, for the purpose specified. 110
19. In a collapsible carriage, the combination with a running-gear frame, of a handle connected to said frame; wheels; wheel-supports having arms thereon, pivotally secured to said frame; levers pivoted on said frame, arranged to engage said arms on said wheel-supports; links connecting the upper ends of said levers to said handle; a foot-rest of flexible material; an adjustable support for said foot-rest; a pocket arranged below said foot-rest, having sides adapted to serve as sides for said foot-rest; and straps connected to said pocket and to the lower ends of said levers, whereby said pocket and foot-rest are lifted when the structure is collapsed, for the purpose specified. 115
20. In a collapsible carriage, the combination with a running-gear frame, of a handle pivotally connected to said frame; wheels; wheel-supports having arms thereon, pivotally secured to said frame; levers pivoted on said frame, arranged to engage said arms on said wheel-supports; and links connecting said levers to said handle whereby said levers are actuated to collapse or erect said wheel-supports by the manipulation of said handle. 120
21. In a collapsible carriage, the combination with a running-gear frame, of a handle pivotally connected to said frame; wheels; wheel-supports having arms thereon, pivotally secured to said frame; levers pivoted on said frame, arranged to engage said arms on said wheel-supports; links connecting the upper ends of said levers to said handle; a seat; a foot-rest; a pocket arranged below said foot-rest, having sides adapted to serve as sides for said foot-rest and straps connected to said pocket and to the lower ends of said levers, whereby said pocket and foot-rest are lifted when the structure is collapsed, for the purpose specified. 125
22. In a collapsible carriage, the combination with a running-gear frame, of a handle pivotally connected to said frame; wheels; wheel-supports having arms thereon, pivotally secured to said frame; levers pivoted on said frame, arranged to engage said arms on said wheel-supports; links connecting the upper ends of said levers to said handle; a bail-like locking-bar pivoted to said frame; links connecting said bar to said levers; a seat; a foot-rest of flexible material; an adjustable support for said foot-rest; and connections from said foot-rest to said levers whereby said foot-rest is lifted when the structure is collapsed, for the purpose specified. 130
23. In a collapsible carriage, the combination with a running-gear frame, of a handle pivotally connected to said frame; wheels; wheel-supports having arms thereon, pivotally secured to said frame; levers pivoted on said frame, arranged to engage said arms on said wheel-supports; links connecting the upper ends of said levers to said handle; a seat; a foot-rest of flexible material; an adjustable support for said foot-rest; and connections from said foot-rest to said levers whereby said foot-rest is lifted when the structure is collapsed, for the purpose specified. 135
24. In a collapsible carriage, the combination with a running-gear frame, of a handle pivotally connected to said frame; wheels; wheel-supports having arms thereon, pivotally secured to said frame; levers pivoted on said frame, arranged to engage said arms on said wheel-supports; links connecting the upper ends of said levers to said handle; a bail-like locking-bar pivoted to said frame; links connecting said bar to said levers; a seat; a foot-rest of flexible material; and an adjustable support for said foot-rest, for the purpose specified. 140
25. In a collapsible carriage, the combination with a running-gear frame, of a handle connected to said frame; wheels; wheel-supports having arms thereon, pivotally secured to said frame; levers pivoted on said frame, arranged to engage said arms on said wheel-supports; links connecting the upper ends of said levers to said handle; a seat; a foot-rest of flexible material; and an adjustable support for said foot-rest, for the purpose specified. 145
26. In a folding carriage, the combination with a running-gear frame, of a handle pivotally connected to said frame; wheels; wheel-supports having arms thereon, pivotally secured to said frame; levers pivoted on said frame, arranged to engage said arms on said wheel-supports; and links connecting said levers to said handle whereby said levers are actuated to collapse or erect said wheel-supports by the manipulation of said handle. 150
27. In a folding carriage, the combination with a running-gear frame, of a handle pivotally connected to said frame; wheels; wheel-supports having arms, pivotally secured to said frame; levers pivoted to said frame connected to said arms on said wheel-supports; and operating connections for the levers to the handle whereby said levers are actuated to throw said wheel-supports inwardly when said handle is swung forwardly. 155

28. In a folding carriage, the combination with a running-gear frame, of wheels; wheel-supports having arms thereon, pivotally secured to said frame; levers pivoted on said frame connected to said arms on said wheel-supports whereby said wheel-supports are collapsed or erected by the manipulation of said levers.
29. In a folding carriage, the combination with a running gear frame, of wheels; wheel supports pivotally secured to said frame; a pair of levers; operating connections for said levers to said wheel supports, whereby said wheel supports are collapsed or erected; and held in their collapsed or erected position by said levers; a bail-like locking bar pivoted to said frame, and links connecting said locking bar to said levers.
- 10 30. In a collapsible carriage, the combination with a running-gear frame, of wheels; wheel-supports; levers connected to said wheel-supports whereby the same are folded or erected when said levers are actuated; a seat; a supporting-bar for the forward end of said seat having downturned ends pivoted on said levers; a spring support for the rear end of said seat comprising tubular casings pivoted to said frame, coiled springs arranged in said casings, and a cross-bar pivotally secured to said seat arranged to rest on said spring having downturned ends arranged through the bottoms of said casings; and a back for said seat pivotally secured thereto, adapted to fold forwardly thereon, for the purpose specified.
- 20 31. In a collapsible carriage, the combination with a running-gear frame, of wheels; wheel-supports; levers connected to said wheel-supports whereby the same are folded or erected when said levers are actuated; a seat, pivotally connected to said levers at its forward end; a support for the rear end of said seat pivoted thereto and to said frame, for the purpose specified.
- 25 32. In a collapsible carriage, the combination with a running-gear frame, of wheel-supports; levers connected to said wheel-supports whereby said wheel-supports are folded inwardly or erected by the actuation of said levers; a seat; a foot-rest of flexible material; a pivoted bail-like support for the forward end of said foot-rest; a pocket of flexible material arranged below said foot-rest having sides adapted to serve as sides for said foot-rest; and straps connected to said pocket and to the lower ends of said levers whereby said pocket and foot-rest are lifted when said levers are actuated to collapse the structure.
- 30 33. In a collapsible carriage, the combination with a running-gear frame, of wheel-supports; levers connected to said wheel-supports in such manner that the one part embraces the other whereby said wheel-supports are folded inwardly or erected by the actuation of said levers; a seat; a foot-rest of flexible material; a pivoted bail-like support for the forward end of said foot-rest; and a pocket of flexible material arranged below said foot-rest having sides adapted to serve as sides for said foot-rest.
- 40 34. In a collapsible carriage, the combination with a running-gear frame, of wheel-supports; levers connected to said wheel-supports whereby said wheel-supports are folded inwardly or erected by the actuation of said levers; a seat; a foot-rest of flexible material; a pocket of flexible material arranged below said foot-rest having sides adapted to serve as sides for said foot-rest; and straps connected to said pocket and to the lower ends of said levers whereby said pocket and foot-rest are lifted when said levers are actuated to collapse the structure.
- 45 35. In a collapsible carriage, the combination with the running-gear frame, of wheel-supports pivotally secured to said frame; levers pivoted on said frame connected to said wheel supports whereby the same are folded inwardly or erected upon the actuation of said levers; a foot-rest; and connections from said levers to said foot-rest whereby said foot-rest is lifted when said levers are actuated to collapse the structure.
- 50 36. In a collapsible carriage, the combination with a seat, of a foot-rest of flexible material; an adjustable support therefor; and a pocket of flexible material arranged
- below said foot-rest having sides adapted to serve as sides for said foot-rest.
37. In a collapsible carriage, the combination with a seat, of a foot-rest of flexible material; and a pocket of flexible material arranged below said foot-rest having sides adapted to serve as sides for said foot-rest.
- 80 38. In a collapsible carriage, the combination with a running-gear frame, of wheel-supports having rearwardly and downwardly inclined crank-like arms thereon pivotally secured to said frame; pivoted levers; loops on said levers arranged to engage said crank-like arms on said wheel-supports whereby, by the actuation of said levers, said wheel-supports are folded inwardly upon each other or extended to operative position and retained in either position as may be desired.
- 85 39. In a collapsible carriage, the combination with a running-gear frame, of wheel-supports having rearwardly and downwardly inclined crank-like arms thereon pivotally secured to said frame; pivoted levers; loops on said levers arranged to engage said crank-like arms on said wheel-supports, whereby, by the actuation of said levers, said wheel-supports are folded inwardly upon each other or extended to operative position.
- 90 40. In a collapsible carriage, the combination with a running gear frame, of wheel supports pivotally mounted thereon; a pair of pivoted levers connected to said wheel supports whereby said wheel supports are folded or extended and held in their folded or extended position by said levers, and a toggle for locking said levers in their erected position.
- 95 41. In a collapsible carriage, the combination with a running gear frame, of pivoted wheel supports; levers connected to said wheel supports in such a manner that the one part embraces and encircles the other, whereby said wheel supports are folded inwardly or erected by the actuation of the levers and held in either position thereby, and connections for said levers whereby they are adapted to serve as braces for said wheel supports when in their erected position.
- 100 42. In a collapsible carriage, the combination with the running-gear frame, of wheel-supports pivotally mounted on said running-gear frame, said wheel-supports having crank-like arms; a pair of levers pivotally secured to said frame above said arms, said levers being connected by a cross-piece at their lower ends; and a connecting brace 110 or cross-piece for said levers arranged so that it lies substantially opposite the said arms on said wheel-supports when in their erected position.
- 105 43. In a collapsible carriage, the combination with the running-gear frame, of wheel-supports pivotally mounted on said running-gear frame, said wheel-supports having crank-like arms; a pair of levers pivotally secured to said frame above said arms; and a connecting brace or cross-piece for said levers arranged so that it lies substantially opposite said arms on said wheel-supports when in their erected position.
- 110 44. In a collapsible carriage, the combination with the running-gear frame, of wheel-supports pivotally mounted on said running-gear frame, said wheel-supports having crank-like arms; and a pair of levers pivotally secured to said frame above said arms, said levers being connected by a cross-piece at their lower ends.
- 115 45. In a collapsible carriage, the combination with the running-gear frame, of wheel-supports having arms thereon pivotally secured to said frame; a pair of pivoted levers arranged to engage said arms on said wheel-supports; and a connecting brace or cross-piece for the lower end of said levers.
- 120 46. In witness whereof, I have hereunto set my hand and seal in the presence of two witnesses.
